Fig. 3

UNITED STATES PATENT OFFICE

FRANK GUST AND EVART W. HAMANN, OF CHICAGO, ILLINOIS

RAIL-LUBRICATING DEVICE

Application filed March 5, 1929. Serial No. 344,122.

This invention relates to a rail lubricating device, and more particularly to a device for automatically applying lubricant to rails of railway tracks at the curves.

An object of this invention is to provide an efficient and positively operating device which will automatically apply lubricant to the inward side of a track rail at a curve through the action of a wheel passing thereover. Another object is to provide a rail lubricating device which will automatically apply the lubricant to the side of the rail with a combined motion of pressing toward the rail and sweeping across said side thereof, in a manner similar to the present manual applying of lubricant with a greasing paddle. A further object is to provide such a device with a paddle-like lubricant applying member, and a feeding member attached thereto and extending into a source of supply or reservoir, and having means for actuating said members to take lubricant from said reservoir and feed it from said applying member to the side of the rail with a sweeping motion. A still further object is to provide such a lubricating device which comprises, in combination with applying means and feeding means, also a reservoir containing therein, and having connected therewith forcing means for positively forcing or feeding the lubricant therethrough to the feeding and applying means, and to have wheel-actuated spring-retracted operating means for operating said forcing means and said feeding means to feed and apply lubricant with a combined pressing and sweeping motion to the side of the rail. Still another object is to provide the device with a supporting plate or member mounted underneath the rail, and on which is mounted the reservoir with the feeding and applying means also the operating lever with the wheel-actuated spring-retracted means thereon, to actuate the force feed means and applying means for positively feeding the lubricant.

These and other objects and advantages are attained with this invention, as will become apparent from the following description, taken in connection with the accom-

panying drawings which form a part of this application.

Referring to the drawings:

Fig. 1 is a plan view of the preferred form of construction embodying our invention, mounted in position on a track rail;

Fig. 2 is a vertical sectional view, taken on line 2—2 of Fig. 1, showing parts in elevation;

Fig. 3 is an end elevation showing the wheel-actuated operating members;

Fig. 4 is an enlarged vertical sectional view, taken on line 4—4 of Fig. 2;

Fig. 5 is a vertical section showing the position of the operating members depressed by a wheel passing thereover;

Fig. 6 is an elevation of the lubricant applying member;

Fig. 7 is a horizontal sectional view, taken on line 7—7 of Fig. 6; and

Fig. 8 is a horizontal sectional view showing the means for forcing and holding the pawl away from the ratchet member.

In the drawings we have illustrated our invention in its preferred form of construction, and in connection with a rail 10 of a railway track over which the wheel 11 travels. This preferred form comprises a supporting plate or member 12 for supporting the mechanism, said plate being mounted beneath the rail and secured thereto, preferably by means of angle members or angle washers 13 and hook bolts or members 14 extending through the plate and angle members, substantially as shown. The plate 12 is provided with depending flanges 15, and these are extended longitudinally beyond the top part of the plate having their lower edges tilted inwardly to provide supporting flanges 16.

A lubricant container or source of supply 17 is provided and is mounted upon the supporting flanges 16. It is preferably in the form of a cylindrical reservoir, and provided with a discharge portion or chamber 18 which is detachably connected to the reservoir by neck parts 17' and 18' on said reservoir and portion, a one-way valve 19 in the neck permitting movement only of the lubricant from said reservoir into said por-

90

85

95

100

tion. Said portion 18 is set in a notch in plate 12 and supported on the plate by ears or lugs 18".

Means 20 is provided for applying the lubricant to the side of the rail, and means 21 for feeding the lubricant to this applying means. This feeding means is preferably in the form of a tube having its upper end opening into the applying means, and having its lower end dipping into the lubricant in the discharge portion or chamber 18 of the reservoir, to force the lubricant, by its downwardly dipping movement, up into said applying means. Said tube 21 is slidably mounted in a ball 22 rotatably mounted in a socket part 23 provided at the top of the chamber, whereby said tube is afforded a sliding and a swinging movement. The tube has a valve 21' in its lower end.

20 The applying means is arranged to serve the purpose of a rail greasing paddle, and is therefore preferably formed like a hollow paddle or channel-shaped, having its mouth or open side facing the inner side of the rail, substantially as shown in the drawings.

The upper open end of feed tube 21 is placed about centrally in this hollow interior of this channel-shaped paddle. A web or plate 24, which preferably contains 30 perforations 25 therein, is mounted centrally across the open mouth of this channel-shaped member to assist in moving the lubricant toward the ends thereof, so as to spread said lubricant and extend it evenly 35 outward beyond the edges at the open mouth of said channel-shaped applying means 20, for applying it evenly to the side of the rail.

Means is provided for forcing the lubricant forward in the reservoir and through 40 its valve 19 into chamber 18, and this means preferably includes a piston 26 slideable in said reservoir and actuated by automatically operated means, as a screw or worm 27 secured to the piston and slidably 45 mounted in sleeve means 28 on a bracket 29 provided in a tubular cap 30 which is detachably mounted on the end of the reservoir, as by pin and slot means 31 and 32. A key 33 in sleeve means 28 engages in a 50 groove in said screw 27 to prevent rotating of said screw; and a ratchet member 34 is mounted in said sleeve means and is threaded on said screw, so that by rotating said ratchet member the screw and piston will 55 be slid longitudinally of the reservoir, but will not rotate due to key 33.

Means for actuating ratchet member 34 and therewith the piston includes a trip rod 35 mounted with bracket means 36 on the 60 outside of supporting flange 16, the inner end of said rod extending at the inside of flange 15 and having a bent operating end 37 thereon. The opposite end of this rod 35 has a bent part 38 extending through a slot 39 in the tubular cap 30 and carrying a pawl

40 thereon for engaging the ratchet teeth 41 on ratchet member 34 to rotate said member for sliding the piston and screw. A nut or member 42 on the end of said screw has a finger 43 for engaging a lug 44 on said pawl to release said pawl and hold it out of operation when said piston and screw arrive adjacent their limit of inward movement; thereby providing means for rendering the forcing means inoperative, to avoid injury to the mechanism when the piston approaches the inner end of the reservoir.

The means for operating the device through the action of a wheel on the track rail comprises an operating lever 46 ful-

crumed at one end in a bracket 47 mounted in plate 12, the forward part or opposite end of said lever being bent upward to form an arm 48 arising through a slot in the plate, adjacent chamber 18, and having a collar 49 pivoted at its upper end, said collar being clamped on tube 21 for swinging and sliding said tube in ball 22 by the operation of said lever. An operating rod 50 has a yoke or knuckle 51 threaded at its lower end to adjust said rod for rails of different heights, and said yoke 51 is pivoted to the intermediate part of lever 46. The forward part of the lever also operates the inner end 37 of trip rod 35. Said rod 50 arises above plate 12 and bears a collar 52 at its upper end, wherein is mounted a stud bolt 53 secured with its head plate 54 onto an operating bar or yoke 55 having its down-turned ends 55' slidably mounted in brackets 56 fastened to the web of the rail. A spring 57 on said rod 50 automatically retracts or returns the various members to the former positions as the wheel leaves the operating bar 55.

Operation of the device:

When a car wheel 11 travels over the track rail 10 and passes over the operating bar 55 of our device attached to said rail, said bar 55 is depressed thereby actuating the operating lever 46 to move the feed tube 21 and dip or slide its lower end through ball 22 into the lubricant in discharge chamber 18, therewith swinging said tube and its attached applying means 20 away from the side of the rail and downwardly, and causing the semi-plastic or grease-like lubricant used herein to be fed or forced upwards through tube 21 into means 20 so as to be extended or bulged outwardly a short distance beyond the edges at the open mouth of said means, for application to the side of the rail thereafter. In the meantime said lever 46 has also actuated trip rod 35 and pawl 40 carried on its end 38 thereby rotating ratchet member 34 and sliding piston 26 inwardly in the reservoir, to forcibly feed a quantity of lubricant through valve 19 into chamber 18, there to be positively fed or forced through the descending tube 21

and the applying means 20 to bulge from the open mouth thereof.

Upon the passing of wheel 11 from the operating bar 55, the retracting spring 57 elevates said bar 55 with operating rod 50 and retracts or returns the operating members to the former positions, thereby swinging and raising feed tube 21 and applying means 20 with its protruding lubricant toward the side of the rail, so as to apply said lubricant to said side with a combined movement of pressing toward said side and sweeping upwardly to spread the lubricant across the same.

15 What we claim as our invention and desire to secure by Letters Patent is:

1. A lubricating device for a track rail, comprising a lubricant container, means for applying lubricant to the side of the rail, tubular feeding means bearing said applying means and extending therefrom into said container, and automatically operated means for dipping one end of said tubular means into the lubricant in said container and also 25 to swing said tubular means with said applying means toward the side of the rail to apply the lubricant thereto with a sweeping movement.

2. A lubricating device for a track rail, comprising a lubricant container, a channel-shaped applying member having its open channel-mouth facing the side of the rail, tubular feeding means bearing said channel-shaped member at the upper end and having 35 the lower end slidable into the lubricant in said container, and means for swinging said tubular means and sliding said lower end into said lubricant in said container to feed it through said open mouth for application 40 to the rail.

3. A rail lubricating device comprising a lubricant container and turnable means thereon, an applying member having an open mouth facing the side of the rail, a feeding member bearing said applying member thereon and being mounted in and swingable with said turnable means to take lubricant from said container and feed it to the applying member, means for forcing lubricant in said container toward said feeding member, and means automatically operated for simultaneously actuating said feeding member and said forcing means to positively feed lubricant to the open mouth of 55 said applying member.

4. A rail lubricating device comprising a reservoir including a contracted part with a discharge chamber thereon, means for forcing lubricant through said reservoir and part into said discharge chamber, means in said part to prevent return of said lubricant from said chamber to said reservoir, a tubular feed member mounted to slide with one end into said chamber and carrying lubricant applying means at its other end, and

means for actuating said tubular member with its applying means and also said forcing means simultaneously.

5. A rail lubricating device comprising a reservoir having a discharge chamber, a lubricant applying member, a tubular feed member bearing said applying member at one end, and universally movable means on said chamber whereby said tubular member has its other end mounted to slide into said chamber and to swing with said means.

6. A rail lubricating device comprising a lubricant container, a tubular member carrying a lubricant applying member at one end, and ball and socket means provided on said container wherein said tubular member slides at its other end to dip into the lubricant in the container and wherewith it swings to move said applying member for applying lubricant with a pressing and sweeping motion across the side of the rail.

7. A rail lubricating device comprising a reservoir having a discharge portion thereon, a piston in said reservoir for forcing lubricant to said portion, a tubular member mounted to move with one end into the lubricant in said portion, an applying member mounted on the other end of said tubular member, and operating means to force said piston and to swing said tubular member with its applying member for applying lubricant with a sweeping motion across the side of the rail.

8. A rail lubricating device comprising a lubricant container, lubricant applying means and feeding means connecting said applying means with said container, a pivoted operating lever pivotally connected with said feeding means to swing the same, and means to operate said lever to swing and slide said feeding means with respect to said container.

9. A rail lubricating device comprising a lubricant container, a supporting member fastened underneath the rail for supporting the device, applying means and feeding means carrying the latter and feeding it from the container and being positioned between the rails, a lever extending underneath the rail and being pivoted on said supporting member and connected to said feeding means, and means on the outward side of the rail to operate said lever to actuate said feeding means for moving said applying means toward and upwards across the side of the rail.

10. A rail lubricating device comprising a supporting member secured underneath the rail, a lubricant container mounted thereon, applying means and a feeding member connecting it with said container, a lever on said supporting member and connected to said feeding member, means for forcing lubricant in said container to said feeding member, and means for automatically op-

erating said lever to actuate said forcing means and said feeding member to feed lubricant positively to said applying means.

11. A rail lubricating device comprising a supporting member fastened under the rail, a lubricant container supported thereon, applying means and feeding means connecting said applying means with said container, means for forcing lubricant in said container to said feeding means, a lever pivoted on said supporting member and pivotally connected to said feeding means and arranged to actuate the latter and the forcing means, and spring retracted means actuated by a wheel on the rail for operating said lever.

12. A rail lubricating device comprising a lubricant container, means for applying lubricant and means for feeding lubricant thereto from the container, lever means connected with said feeding means at one side of the rail, a spring retracted member at the other side of the rail arising from said lever means for operating it in reverse directions, and an operating bar depressed by a wheel on the rail to move said member for operating said lever and feeding and applying means.

13. A rail lubricating device comprising a lubricant container, means for feeding lubricant therefrom and for applying it to the side of the rail, means for forcing lubricant in said container to said feeding and applying means, a lever and means for actuating thereby the forcing means and the feeding and applying means, a spring retracted member arising from said lever, and an operating bar depressed by a wheel on the rail and attached to said member for operating said lever and device to positively force lubricant into said applying means.

14. A lubricating device for a track rail, comprising a supporting member secured underneath the rail, a lubricant container mounted thereon, an applying member, a feeding member carrying said applying member and being movable into said container to feed lubricant therefrom to said applying member, means for forcing lubricant through said container to said feeding member, a lever mounted on said supporting member and being connected to said feeding means for swinging and sliding it with respect to said container, trip means actuated by said lever for operating said forcing means, a spring retracted member for operating said lever in reverse directions, and an operating bar connected to said operating member and actuated by a wheel on the rail for operating the device.

15. In testimony whereof we have signed our names to this specification.

FRANK GUST.
EVART W. HAMANN.
